UNITED STATES PATENT OFFICE.

ELMER U. STEWART, OF SHARON, PENNSYLVANIA.

EXPLOSION-ENGINE.

1,152,859.

Specification of Letters Patent.

Patented Sept. 7, 1915.

Application filed July 25, 1914. Serial No. 853,052.

To all whom it may concern:

Be it known that I, ELMER U. STEWART, a citizen of the United States, residing at Sharon in the county of Mercer and State of Pennsylvania, have invented a new and useful Explosion-Engine, of which the following is a specification.

The present invention relates to improvements in explosion engines, one object of the invention, being the provision of an engine in which each cylinder is provided with a single port, having two branches, one of said branches being the intake branch and the other branch being the exhaust branch, there being disposed for controlling each branch, a reciprocating piston valve, ported intermediate of its ends for controlling the passage of the carbureted charge or the exhaust gases therethrough, such valves being operably connected through the crank shaft so that a four-cycle effect is produced in the engine.

A further object of the present invention, is the provision of means whereby the piston valves are employed to compress air for storage in a tank to act as a starting means to initially start the explosion engine, to operate signals upon a motor car or boat and to inflate the tires upon the motor car to act as an air brake, and to clean out the exhaust and muffler.

A still further object of the present invention, is the provision of a novel lubricating system, by means of which the various frictional parts of the engine are properly lubricated, the circulation of the oil being accomplished by means of a rotary pump.

A still further object of the invention, is the provision of an adjustable radiator cooling fan bracket, whereby the belt may be readily tightened and by means of which the parts are properly supported to the base of the engine.

With the foregoing and other objects in view which will appear as the description proceeds, the invention resides in the combination and arrangement of parts and in the details of construction hereinafter described and claimed, it being understood that changes in the precise embodiment of the invention herein disclosed can be made

within the scope of what is claimed without departing from the spirit of the invention.

In the drawings—Figure 1 is a side elevation taken from the intake and exhaust side of a four cylinder engine embodying the present invention, the valve cylinders of two of the power cylinders being shown in longitudinal section with the crank case being broken away to show the operative connection thereof. Fig. 2 is a cross section taken through one of the power cylinders and one intake valve of one cylinder. Fig. 3 is a section taken on line 3—3 of Fig. 2. Fig. 4 is a plan view of the manifold and air tank of the engine.

Referring to the drawings, the numeral 1 designates the crank case, which has mounted therein, the crank shaft 2, to which is connected a plurality of power piston rods 3, each one of said rods, as clearly shown in Fig. 2, being connected to its piston 4, which is disposed for reciprocation within its power cylinder 5. These cylinders 5, as clearly shown in Fig. 3, are cast two *en bloc* to provide the main casting B and at the upper end of each power cylinder is a single port 6, which by means of the by-pass 7 leads to the respective exhaust and intake branches 8 and 9.

The intake branch 9 is intercepted by means of the cylindrical and vertical bore 12 in which reciprocates the cylindrical combined valve and air pressure producing member 10, the same as illustrated in Fig. 2, being provided with the port 11 intermediate of its ends. The outer end of the branch 9 is in communication with the port 13 which in turn communicates with the intake port or branch 9' of the adjacent power cylinder, the casing 14 being connected to the intake manifold 15 common to both branches 9 and 9'. Disposed in the intake manifold 15 is a tap 16 by means of which air is supplied through the pipe 16', as will later appear.

Intercepting each branch 8 is a vertical bore 17 in which is mounted for reciprocation, the combined exhaust valve and air compressing member 18, this member being provided with the intermediate port 19 by means of which the respective branches 8

and ports 9 may be placed in registration so that the exhaust may be directed through the branch 21 into the exhaust manifold 22.

It will thus be seen that with the single port 6 and by-pass 7, that the intake of the explosion charge is directed therethrough as is also the exhaust of the burnt gases, thus producing a complete scavenging of the by-pass and the upper portion of the power cylinder so that when a charge is drawn therein for compression and explosion, the maximum power will be produced.

Each casting B, as clearly illustrated in Fig. 2, is provided with the water packeting space 23, which surrounds both of the power cylinders and the valve cylinders also, there being provided the connections 24 and 25 so that a complete circulation of water through the jacket is provided.

Connected to each exhaust controlling valve 18 is a piston rod 26, while connected to each intake valve 10 is a piston 27, such pistons as clearly illustrated in Fig. 1, being connected to the counter crank shaft 28; and one end is provided with the extension 29 to which is keyed the noiseless chain sprocket wheel 30 which has trained thereover the chain 32 so that power will be transmitted from the small sprocket wheel 33 keyed upon the crank shaft 2 to properly rotate the counter crank shaft 28 in timed relation to the power pistons. A protecting casing 31 surrounds that portion of the crank shaft and the noiseless chain mechanism so that no dirt or dust will be permitted to affect the same.

Each of the respective valve members 10 and 18 are counter bored in their upper ends as at 34 to reduce the weight thereof, the same being sealed by the removable plug or cap 35. Thus these members constitute an air compression member, the valve 46 controlling the introduction of the air within the upper end of the respective cylinders 12 and 17 upon the down stroke of the members 10 and 18 while the compressed air is led through the pipe 37 past the check valve 38 and the manually controlled valve 39 to the air directing pipe 40, said pipe 40 being directly connected to the storage tank 42, which as illustrated in Fig. 2, is supported by the brackets 43 upon one side of the engine. This tank 42 is provided with the manually controlled valve 44 and the nipple connection 45, by means of which air may be directed therefrom to be used in starting the explosion engine, pumping tires and operating signal devices, and air brake, and to clean the exhaust and muffler.

The upper ends of the respective chambers 12 and 17 are closed by the removable plugs 36 and 36' to which as before stated, the intake valve 46 and the air directing pipe 37 are connected.

Connected to the pipe 40, one to each in-

take manifold 14, is a valve casing 41, which is in reality a throttle valve, that provides for communication between the pipe 40 and the air directing pipe 16', so that air under pressure may be directed into the intake manifold to assist in accelerating the carbureted air charge and thus assisting in directing the same to the explosion chamber of the engine.

A pet cock 47 is connected in the head of each power cylinder 5, so that a liquid fuel charge may be introduced, while the removable plug 48 is also connected therein and carries the spark plug 49.

When the present device is used as an air brake, the flow of carbureted air to the power cylinder is cut-off and the air drawn into the power cylinders is cushioned to retard the power pistons and thus produce a gradual braking effect. To accomplish this, the spark (not shown) is retarded and the throttle is closed in the intake manifold so that air that might pass back through the intake manifold will not pass through the carburetor and open the valve 41. The valve 100, which is located at any desired point in the exhaust manifold, is operated to retard or permit free passage of the air through the exhaust manifold 22, the air for operating the power pistons being admitted through the port 16' into the intake manifold. By manipulating the valve 100, the exhaust is retarded or freed, thus regulating the cushioning or braking effect of the compressed air.

A safety valve 101 to prevent the too great pressure of air in the tank is provided.

The usual connections with the crank shaft for operating a pump and magneto may be employed.

In order to provide a means for properly lubricating the various frictional parts of the engine, the lower portion of the crank case 1 as at 50 constitutes the oil receptacle, the same having its bottom inclined so that the oil will flow toward one end thereof to the rotary pump 55 which is operated through the shaft 58, and the pinions 59 and 60, the pinion 60 being operably connected to the counter crank shaft 28 so that the rotary pump will be properly operated during the operation of the engine. The screen S is mounted within the crank case so as to prevent gritty substances from entering the oil in the lower portion or reservoir 50. Disposed one to each of the cranks of the crank shaft 2, is a hingedly swinging oil receptacle 53 which is provided with trunnions 53' and the oil directing member 54 by means of which as the crank shaft rotates, the connection thereof to its respective piston rod will be properly lubricated.

In order to provide a means for filling the reservoir 50, the pipe 52 as illustrated in Fig. 2, is connected to the crank case and

leads from a lower point to the upper edge of the directing shield 51, so that the oil will be properly directed to the bottom of the crank case.

5 In order to ascertain at a glance the amount of oil within the reservoir 50, a float 61 is mounted at a point adjacent the pump 55, and has a rod 62 extending upwardly and carrying the indicator 63 which 10 is adjacent to the index 64 upon the upper portion of the base of the engine.

By mounting the oil receptacles 53, for swinging movements, they maintain a level position at all times.

15 Connected at the opposite end of the base of the engine is a bracket 65, which is provided with a plate 66 having the slot 68 for the reception of the adjusting screw 67, and also carries the screw 69, by means of 20 which the stub shaft 70 which is a hollow shaft may be properly clamped in place. This hollow shaft has in communication therewith, a lubricant supplying tube 71 and the grease cup 72, by means of which 25 lubricant may be supplied internally through the shaft to the hub 73 which carries the cooling fan 74 and the driving spool 75. The driving spool 75 is operably connected by means of a belt 76 to the spool 77 30 fixed upon the crank shaft, the screw connections 67 and 69 being provided to adjust the shaft 70 so that the belt 76 may be properly tightened at all times.

What is claimed is:

35 1. An explosion engine, including a power cylinder having a single port adjacent the top thereof and two branch conduits leading therefrom and constituting the intake and exhaust conduits of the engine, two valve 40 cylinders disposed in parallel to the engine and power cylinder, the bore of one of the valve cylinders bisecting each conduit, two cylindrical reciprocating valves one mounted in each valve cylinder, each valve being 45 provided with a diametrically disposed port for registration with the conduit, a crank shaft, a power piston connected thereto, a counter shaft operably connected to the crank shaft and to both valves, the upper 50 end of the valve cylinders being closed, an air intake valve mounted in the closed end of each valve cylinder, an air directing pipe provided with a check valve leading therefrom, an air storage reservoir in communication with the last conduit, whereby the 55 valves form air supplying means for the tank, a pipe leading from the air supplying pipe, and an intake manifold connected to one of the conduits of the power cylinder 60 and to the last mentioned pipe, whereby air is directed thereto.

65 2. An explosion engine, including a casting provided with two parallel power cylinders each one of which is provided with a port adjacent the top thereof leading into a

channel extended downwardly and parallel with the walls of the cylinder, said casting being further provided with two divergently disposed gas conducting passages leading from the lower end of the channel to 70 the exterior of the engine, the two adjacent passages for both power cylinders constituting the intake passages therefor while the two outer ones constitute the exhaust passages therefor, an intake manifold connected to both of the inlet ends of the two intake 75 passages, an exhaust manifold connected to the outer ends of both exhaust passages, four valves bisecting the respective intake and exhaust passages, each of said valves being 80 provided with a diametrically disposed port intermediate of its ends for registration with its respective passage, a power piston mounted in each cylinder, a crank shaft operably connected thereto, a counter shaft operably connected to the crank shaft and to all of the valves, the upper ends of each of the respective valves constituting an air compressing means, a valve controlled intake pipe connected to supply air to each 85 valve, a valve controlled outlet pipe leading from each valve cylinder, a pipe common to all of the outlet pipes, an air storage reservoir connected to the last pipe, and a pipe connected to the last mentioned pipe and to 90 the intake manifold for supplying air to the intake manifold to accelerate the fuel.

3. An explosion engine, including a casting provided with two parallel power cylinders each one of which is provided with a 100 port adjacent the top thereof leading into a channel extended downwardly and parallel with the walls of the cylinder, said casting being further provided with two divergently disposed gas conducting passages 105 leading from the lower end of the channel to the exterior of the engine, the two adjacent passages for both power cylinders constituting the intake passages therefor while the outer ones constitute the exhaust passages 110 therefor, an intake manifold connected to both of the inlet ends of the two intake passages, an exhaust manifold connected to the outer ends of both exhaust passages, said casting being provided with four vertical bores 115 disposed at their upper ends and in parallel with the power cylinders, said bores intersecting the respective passages, a cylindrical valve mounted for reciprocation within each bore and provided with a diametrically disposed port intermediate of its ends for controlling the passage of gas through its respective passages, two power pistons, a crank shaft operably connected thereto, a counter shaft operably connected to the 120 crank shaft and all of the reciprocating valves, a valve controlled air inlet member connected in the upper end of each valve cylinder, a valve controlled outlet pipe connected thereto, a single pipe connected to all 125 130

of the latter pipes, an air reservoir operably connected to the single pipe to receive the compressed air from all of the valve cylinders, and a pipe leading from the last pipe to the intake manifold for supplying air to the intake manifold to accelerate the fuel charge.

In testimony that I claim the foregoing as my own, I have hereto affixed my signature in the presence of two witnesses.

ELMER U. STEWART.
